UNITED STATES PATENT OFFICE

GIACOMO MEMINI, OF MILAN, ITALY

CARBURETOR

Application filed January 26, 1923, Serial No. 615,050, and in Italy February 25, 1922.

The object of the present invention is to vary the amount of the fuel fed through the nozzle of a carburetor for internal combustion engines, so that less fuel is supplied progressively and proportionately as the suction at said nozzle increases, this effect being obtained automatically and without employment of any movable controlling device.

In the attached drawing, Fig. 1 shows diagrammatically a longitudinal section taken on the line 1—1, Fig. 2, and Fig. 2 a cross section, of this device for actuating said control in a common carburetor, taken on the line 2—2, Fig. 1. The arrangement may 15 vary according to the shape of the carburetor.

1 represents the float chamber, 2 the passage connecting it with the mixing chamber through the restricted orifice 3 which leads into a chamber 10 containing the two extremities of an annular passage 5°, 5, 5', 5'', 5''' ; one of these extremities communicating directly with the part 5° of said annular passage, which is of fairly ample section and which communicates through the nozzle 4 25 with the mixing chamber 9 in the Venturi throat 7 of the latter, and in certain cases through the narrow passage 6 (in the portion 5'' and at a certain distance from the nozzle 4) with the atmosphere; the portion 30 5''', which forms the other extremity of the annular passage, is of lesser cross section than the rest of the passage. 8 is the throttle valve which closes the mixing chamber.

The operation of the device is as follows: 35 From the float chamber 1 the fuel passes, through the passage 2 to the restricted orifice 3, from the orifice 3 the fuel rises in the chamber 10 passage 5' and the nozzle 4, up to the level existing in 1.

40 When the throttle valve 8 is slightly opened and the engine started up, a low depression is exerted through the Venturi throat 7 and a small depression through the nozzle 4, so that said nozzle 4 will be continuously fed 45 by the orifice 3, not owing to the suction on the latter at this moment, but because the fuel has a tendency to pass from the float chamber 1, and—according to the well-known law of the constant level of liquids—rise to the 50 same level in the passages communicating

with it. If the opening of the throttle valve 8 be increased, the depression through the Venturi throat 7, and consequently through the nozzle 4, will be greater; but the portions 5', 5 and 10 will be emptied and through the portion 5° there will be formed a continuous passage from the orifice 3 to the nozzle 4; and through 5''', 5'', 5', 5, a depression will be exerted in chamber 10 due to the passage of air from the passage 5 to the nozzle so that the flow of fuel from 3 to 5° will be distributed or counteracted by eddies forming in the lower part of chamber 10 where the depression acts upon the surface of the fuel. The portion 5° is at this time either completely or almost completely filled with fuel thereby hindering or stopping entirely the flow of air therethrough.

On opening the throttle valve 8 still more, or completely, there will be still greater depression on the nozzle 4, and at the same time there will also be increased depression in the passages 5, 5', 5'' and 5''', and as this depression exerts an opposite action on the main suction through 5° there will be at this moment two opposite forces, that is, the orifice 3 will be no longer subjected to the total depression of the nozzle 4, through portion 5°, but to a much lesser degree in view of the depression exerted through 5''' and to the resulting eddies within chamber 10; therefore the fuel can reach the nozzle 4 through 5° only in relatively small quantities.

In the portion 5'' there is a restricted air passage 6, which in certain cases may not be necessary, the general effect of same being to delay or partially counteract the effect of the suction through 5''', 5'', 5', 5 as the depression exerted from the nozzle 4 only influences the portion 5''' when it has increased to such a value as to overcome the air supplying capacity of the restricted passage 6, and therefore the portion 5'' operates in the above described manner only when the depression from 4 exceeds a predetermined value.

Said passage 6 is also provided with the object of moderating the action of the controlling device, so that the latter should not be too strong and not hinder the working of the carburetor under full load.

What I claim is:—

1. A device for the automatic control of the fuel flow from the fuel nozzle of a carburetor, comprising a fuel chamber between the usual float chamber and the fuel nozzle, a restricted orifice for the supply of fuel to said chamber, the cross-sectional area of this orifice being less than that of the nozzle, a fuel passage for the supply of fuel from the said chamber to the fuel nozzle, and an air passage having a portion of lesser cross-sectional area than the first passage and leading from the top of said chamber to the nozzle to create eddies in such chamber and thus oppose the flow of fuel to the nozzle in proportion as the depression at the nozzle increases.
2. A device for the automatic control of the fuel flow from the fuel nozzle of a carburetor, comprising a fuel chamber between the usual float chamber and the fuel nozzle, means for restricting the flow of fuel to the said chamber, a fuel supply passage from the said chamber to the nozzle, and an air passage of greater length but having a portion thereof of lesser cross-sectional area than the first passage and also providing communication between the said chamber and nozzle to create eddies in said chamber and thus oppose the flow of fuel to the nozzle in proportion as the depression at the nozzle increases.
3. A device for the automatic control of the fuel flow from the fuel nozzle of a carburetor, comprising a fuel chamber between the usual float chamber and the fuel nozzle, means for restricting the flow of fuel from the float chamber, a fuel supply passage leading from the said fuel chamber to the nozzle, an air passage of greater length than the first passage but having a part of lesser cross-sectional area and also providing communication between such fuel chamber and the nozzle for the purpose of creating eddies in the said fuel chamber and thus opposing the flow of fuel to the nozzle in proportion as the depression at the nozzle increases, and a restricted passage providing communication between the said air passage and the atmosphere.
4. A device for the automatic control of the fuel flow from the fuel nozzle of a carburetor, comprising a fuel chamber between the usual float chamber and the fuel nozzle, a fuel supply passage from the lower part of said chamber to the nozzle, an air passage having a portion of lesser cross-sectional area than the first passage and providing communication between the upper part of said chamber and the fuel nozzle to create eddies in the lower part of said chamber and thus oppose the flow of fuel to the nozzle in proportion as the depression at the nozzle increases, and a member located between the said chamber and the usual float chamber

and having a restricted orifice for the passage of fuel from the float chamber.

Signed at Milan, Italy, this 5th day of January, 1923.
